UNITED STATES PATENT OFFICE.

GEORGE ALANSON MASON, OF 109 FARRINGDON ROAD, COUNTY OF MIDDLESEX, ENGLAND.

SHORT-CIRCUITING DEVICE FOR MAGNETO-CALLS.

SPECIFICATION forming part of Letters Patent No. 339,672, dated April 13, 1886.

Application filed May 14, 1885. Serial No. 165,463. (No model.) Patented in England March 25, 1885, No. 3,850.

To all whom it may concern:

Be it known that I, GEORGE ALANSON MASON, engineer, a citizen of the United States of America, and residing at 109 Farringdon Road, in the county of Middlesex, England, have invented certain Improvements in Shunts or Contact-Variers or Automatic Cut-Outs or Short-Circuiter for Magneto Call or Signaling Bells, or for other Purposes, (for 10 which I have applied for a patent in Great Britain, No. 3,850, dated March 25, 1885,) of which the following is a specification.

My invention has for its object to provide a simple and efficient arrangement for varying 15 the contact for diverting the passage of a current of electricity as required, the said arrangement being more especially applicable for use with magneto signaling or call bells, but being also applicable to other purposes 20 where a shunt or circuit-varier or automatic cut-out or short-circuiter is required.

According to my invention I actuate the armature of the magneto-electric generator by means of a shaft and a crank-handle in the 25 ordinary way; but I connect the crank-handle to the shaft so that when first operated it has a movement of rotation imparted to it independently of the shaft sufficient to cause a 30 spring to be removed from the short-circuiting contact which it made when the parts were in their normal position, and so that when the crank is operated it throws the armature into the circuit and maintains it in circuit while the crank is rotated; but as soon 35 as the crank-handle is released the said spring or contact-piece automatically returns to its original position, to short-circuit or cut out the coils of the magneto-armature. I effect this by means of a spring contact-strip of a bowed 40 form, and attached at one end to the shaft and at the other end to the collar of the crank-handle, the attachment to the shaft being preferably effected by a post rising through a slot in the said collar, so that the said post serves 45 as a stop, the slot allowing the necessary movement of the crank-handle to contract the spring and remove it from its short-circuiting contact, which short-circuiting contact is preferably made by a collar-piece surrounding the 50 path through which the spring contact-piece travels as the crank-handle is rotated, so that

in whatever position the crank-handle is left after it is released, the spring, on automatically expanding, will bear upon some portion of the said collar.

In the drawings, Figures 1 and 2 are views at right angles to each other of mechanism constructed according to my invention. Fig. 2 shows the device in its position for making one contact or short-circuiting, and Fig. 3 60 shows the position when this contact is withdrawn for shunting the current in the required direction.

A is a shaft mounted in a casing or support, B, and C is a crank-handle, and D is a band 65 or gear wheel on the said shaft. These may be of the ordinary kind; but the crank-handle is connected to the shaft by a pin or post, a, on the shaft passing through a slot, d², in the collar d of the handle, so that when the handle is operated it moves for a part of a revolution without turning the shaft A until the end of the slot d² comes against the post a. A spring-strip, E, is secured at one end to the post a and at its other end to the collar d. 70 When the parts are in their normal position, as shown in Fig. 2, the said spring-strip E bears upon a ring, f, of metal, forming a lining to the box or bearing on which the shaft A is mounted, or otherwise surrounding the 75 part at which the spring-strip E is situated. When the spring-strip E bears on this ring f, the required circuit for the current during the time the handle is not operated is completed—say, for example, a short-circuit past the coils 80 of the armature of the magneto-machine, by which a current is generated when the handle is rotated.

On the handle being rotated, the slot d² first allows the collar d to move round on the shaft 90 A for a short distance, sufficient to contract the spring-strip E and withdraw it from contact with the ring f, thus breaking the circuit before completed, and compelling the current to pass through any other necessary 95 course—say through the coils of the armature of the magneto-machine. When the end of the slot d² comes against the post a, as shown in Fig. 3, the handle C and shaft A rotate together to divert the current or to cause the 100 generation of the current in the usual way. When the handle is released, the spring-strip

E automatically returns to its normal position and completes the short or other circuit through the ring f.

I claim—

- 5 1. The combination, with a curved or circular contact device, a handle or crank, and a shaft, of the curved spring connected at one end to the handle or crank and at the other end to the shaft, and means, substantially as described, for loosely securing the handle and shaft to each other, so as to allow a limited amount of play to the handle with respect to the shaft, substantially as and for the purpose described.
- 15 2. A short-circuiting apparatus which comprises in its construction shaft A, handle or crank C, spring E, connected at one end with the handle or crank and at the other end to

the shaft, and a contact against which the spring normally bears, substantially as and for the purpose described.

3. The combination of the short-circuiting contact device f, shaft A, post or pin a, handle or crank C, having slotted collar d, and spring E, connected by one of its ends to the post a and by its other end to the collar d, substantially as and for the purpose described.

In testimony whereof I have signed my name to this specification in the presence of two subscribing witnesses.

GEORGE ALANSON MASON.
